DENTAL CONSOLE

Richard W. Lanigan, Arlington Heights, Ill., assignor to American Hospital Supply Corporation, Evanston, Ill., a corporation of Illinois

Filed Mar. 2, 1965, Ser. No. 84,045

Term of patent 14 years

(Cl. D24—1)

FIG. 1 is a side elevational view of a dental console embodying the present invention;

FIG. 2 is a front elevational view;

FIG. 3 is an elevational view of an opposite side of the console;

FIG. 4 is a rear elevational view;

FIG. 5 is a top plan view.

In FIGURES 2-5, a portion of a tray arm assembly, which forms no part of the console cabinet design, is shown in broken lines for purposes of illustration and to give a clearer understanding of the structure of the present design and its environment.

I claim:

The ornamental design for a dental console, substantially as shown and described.
